UNITED STATES PATENT OFFICE.

ALBERT D. PENTZ, OF ELIZABETH, NEW JERSEY, ASSIGNOR TO HIMSELF,
AND ABRAHAM VANDERBEEK, OF NEW YORK, N. Y.

BORING-ENGINE.

SPECIFICATION forming part of Letters Patent No. 461,202, dated October 13, 1891.

Application filed February 26, 1891. Serial No. 382,950. (No model.)

To all whom it may concern:

Be it known that I, ALBERT D. PENTZ, a citizen of the United States, residing at Elizabeth, in the county of Union and State of New Jersey, have invented an Improvement 5 in Boring-Engines, of which the following is a specification.

The present invention is an improvement upon that set forth in Letters Patent No. 408,259, granted to me August 6, 1889; and the said invention relates to the devices and their combinations, hereinafter set forth, whereby the capacity of the said machine is very much increased and the facility for handling 15 the article that is being operated upon is also increased, and the boring-bar and parts that carry the tool and the article operated upon are stiffened and vibration of the parts is lessened.

I have reduced this invention to practice by constructing the machine illustrated in the accompanying drawings, wherein—

Figure 1 is a vertical section of the apparatus with the spindle in elevation. Fig. 2 is a horizontal plan at the line $x-x$, Fig. 1. Fig. 3 is a general perspective in smaller size, showing the positions of the parts. Fig. 4 is a detached view of the pendent drop. Fig. 5 is a sectional plan at the line $y-y$ and in larger 25 size. Fig. 6 is a plan view, partially in section, of the knee-plate and saddle. Fig. 7 is a sectional plan at one end of the platen. Fig. 8 is an end view thereof and of the revolving angle-plate. Fig. 9 is an elevation. Fig. 10 is a plan of said revolving angle-plate 30 and the parts connected therewith. Fig. 11 is a section at the line $y'-y'$ of Fig. 9. Fig. 12 is a section in larger size at the line $z-z$ of Fig. 1, and Fig. 13 is a section in larger size of a 35 portion of the platen and swivel-plate.

The main column A, Fig. 1, is preferably rectangular and provided with a flaring base or foot, and the top of the column is extended upwardly to form the standards or frames A', 40 that are connected at their upper ends by the tube B', through which passes the supporting-arm B, and this tube B' is slotted at one side and provided with screws a , by which the supporting-arm can be clamped firmly after 45 it has been adjusted to the proper position, and this supporting-arm B, being circular and

of uniform size, can be slipped endwise through the clamping-tube B' to any desired extent to adapt the machine to the article that is being bored or turned, and such supporting-arm can 55 also be turned in the tube B' to bring the center of the bushing b in the pendent arm C in line with the axis of the boring-bar or other tool that is rotated by the spindle D, as herein-after described, and usually the lower end of 60 the pendent arm C is slotted, as shown at C', Figs. 3 and 4, in order that such pendent arm may be stiffened and clamped in position rigidly by a screw 2 in said slot, that is tapped into the front edge of the knee-plate E, Figs. 65 1, 3, and 6, hereinafter described. This pendent arm being slotted, the knee-plate and the parts carried by it can be raised or lowered during the operations of the machine after the clamping-screw 2, Figs. 3, and 4, has been loosened. 70 This slotted pendent arm is especially advantageous when a milling-tool rotated by the spindle D is made to act at different heights upon the surface of an article that is supported by the knee-plate and the slide-rests 75 thereof.

The front end of the supporting-arm B terminates in a hollow vertical cylinder c , split open or separated at one side and provided with clamping-screws 3, into which cylinder 80 the upper end of the pendent arm C is received and securely held by the screws, so that the bushing b may be brought into line with the axis of the spindle D. It is preferable to provide a flange at the upper end of 85 the arm C to form a stop against the cylinder c when the bushing b is at the proper distance from the axis of the arm B.

One peculiarity of the present invention relates to the construction of the spindle and 90 the parts for driving the same. The spindle D is tubular, having a flange 4 at the outer end and an external screw upon which the chuck can be secured, as in a lathe, and this spindle D passes through the frames A' A', 95 and there is a split nut 5 around a screw-thread at the back surface of the front frame A', to prevent the spindle drawing forward, and this nut 5 is clamped firmly after being adjusted by a transverse screw across the 100 split, as seen in Fig. 2, and there is a washer between the nut 5 and the back face of the

standard A'. The bushings 6 and 7 within the standard A' and around the spindle D are conical, with a washer at 8, upon which the thrust is received in the milling or turning operation.

The driving-pulleys F have two or more steps in the cone of pulleys for the reception of the driving-belt from any suitable counter-shaft. The driving-pulleys are formed of a shell, preferably of cast-iron, received upon the tubular hub F', having a flange at one end, the rim of which passes within the largest edge of the pulley. By this construction I am enabled to cut a pinion 9 at one end of the tubular hub F' when the hub is separate from the pulley, and such pinion projects beyond the end of the pulley when the parts are put together, and the shell of the pulley is shrunk upon the tubular hub, and its flange may be secured by pins, so that the tubular hub and pulleys are firmly connected together; but they are loose on the spindle D, so as to revolve freely around the same.

Upon the spindle D is a gear-wheel G, which is firmly connected to the spindle D by a key 10, and this key passes through a mortise in the spindle D, so as to firmly connect the gear-wheel and the spindle, and the inner end of this key 10 passes into a longitudinal slot or key-seat in the tool-holding tube D', Fig. 2, hereinafter described, and there is a movable lock 11 upon the gear-wheel G to lock into a notch within the flange on the tubular hub F' for connecting the gear-wheel G and the driving-pulleys, so that the power may be applied directly from the driving-pulleys F to the spindle D, or when this lock 11 is disconnected from the hub F' the pulleys F are free to revolve around the spindle D, and the motion is taken from the pinion 9 to the counter-shaft H by the gear-wheel I and communicated from the counter-shaft H by the pinion I', which is brought into gear with the wheel G. I find it advantageous to place upon the counter-shaft a key 12, with a central collar, so that the gear I can be slipped upon the key 12 to rotate the shaft H from the pinion 9 whenever the counter-shaft is to be rotated, and the pinion I' is to be slipped upon the key 12 and receive its motion therefrom whenever the lock 11 is disconnected from the hub F', so that the spindle is rotated with a slower movement through the gearing and counter-shaft. By this construction I am enabled to give a motion to the counter-shaft for driving other parts of the machine, as hereinafter described, and this motion can be continuous and uniform regardless of whether the spindle is receiving a fast or a slow motion. Hence I am enabled to take a feeding motion from the counter-shaft regardless of the speed of the spindle, and I provide upon the counter-shaft a cone of pulleys L and a cone of pulleys M on a stud supported by the column A, and a belt from the pulleys L to M, and there is also a feeding-shaft N, with a cone-pulley N', and a belt leading to the cone-pulley M,

so that by this arrangement of pulleys a faster or slower movement can be given to the feed-shaft N by shifting the belts on the respective cone-pulleys, and it is usually necessary to cross the belt leading from the cone M to the cone-pulleys N', and this feed-shaft N is provided with a movable extension-shaft O, with universal joints O' O' at the respective ends, 75 and these universal joints may be of any desired character; but I have represented them as similar to the joints in my patent, No. 433,304, granted July 29, 1890.

From the rear standard or frame A' a tubular sleeve A' extends horizontally and in line with the spindle D. This sleeve A' is bored to receive the end of the spindle and turned off and faced to fit the opening in the standard A', so as to be perfectly in line with the 80 spindle, and within this sleeve A' is a tubular nut K, and within such tubular nut is a tubular screw K', having a collar, as seen in Fig 2, and a gear-wheel e, permanently connected to such tubular screw K' by a key and nut, so that 85 when this gear-wheel e is rotated the tubular screw K' will be revolved. The tubular nut K is allowed to slide endwise upon a key or feather attached within the sleeve A' when acted upon by the screw K'; but such tubular 90 nut K does not revolve, and it is connected at its inner end with the tool-holding tube D' by a neck or collar upon the end of the tubular nut K, received into a corresponding recess in the tool-holding tube D', so that the 95 latter is free to revolve with the spindle D, and this tool-holding tube is slotted, as aforesaid, for the inner end of the key 10, so that this tool-holding tube may be projected or retracted by the screw K' and the tubular 100 nut K during the operations of boring or 105 milling as performed in this machine.

It is to be understood that the feed-screw K' receives through it the boring-bar or other tool, and this boring-bar is of any suitable 110 length; but it is preferably made to fit the tool-holding tube D', or any suitable tool is clamped by a chuck held within the taper-hole in the front end of the tube D', the spindle and tool-holding tube always revolving 115 together. The boring bar or tool passes through and is supported by the bushing in the pendent drop or arm C. In cases where a milling-tool is made use of it is attached to the screw on the end of the spindle D and 120 the feed-screw is thrown out of action. It is to be understood that boring and drilling tools that require a feed in the direction of the axis of the spindle are held within the tube D', and that milling-cutters that are fed by 125 a movement of the article operated upon are secured to the screw on the end of the spindle.

In order to rotate the feed-screw in either direction, I make use of the feed-shaft P, which 130 is in the same horizontal plane, or nearly so, as the spindle, but at an angle, as seen in Fig. 2, and it is supported by bracket-arms from the column A, and there is a hand-wheel

P' at the front end of such feed-shaft P, and there is a gear-wheel e' on the feed-shaft P', gearing into the wheel e upon the tubular feed-screw K', so that such feed-screw can be rotated by the hand-wheel P'.

In operating upon metal by either boring, milling, or cutting tools the tool is often broken or worn by being fed either too rapidly or by the tool encountering some unexpected obstacle. To prevent injury to the tool, the gear e' is connected to the feed-shaft P frictionally, so that the shaft P may continue to revolve without moving the feed-screw in cases where the tool meets with un-
due resistance. I make the frictional device
15 that is applied to the gear e' of a collar 13 per-
manently fastened to the feed-shaft P and a
conical washer 14 and screw 15. The washer
14 is rotated with the shaft P by a feather or
20 interlocking lugs, and the screw 15 applies
more or less friction to the gear e' between the
edges of the conical washer and the edges of
the collar P at the opposite faces of the gear
e'; and I provide an oiling-hole through the
25 conical washer 14 and a hole passing through
the gear e', whereby both frictional surfaces
can be properly lubricated by oil that is re-
tained within the cavity of the conical washer.

In order to rotate the feed-screw P with
30 uniformity, I make use of a worm g upon the
spindle D, and this drives a worm-pinion h
upon the inclined shaft i, at the upper and
outer end of which is a bevel-gear k, gearing
35 with the bevel-gears l and m upon the feed-
shaft P, which gears l and m are loose, and
each gear is provided with a clutch upon its
inner face, between which is the sliding clutch
n upon a feather upon the feed-shaft P, and
40 there is a lever o, by which the clutch n
can be shifted to couple the bevel-gear l
or the bevel-gear m with the feed-shaft, in
order that said feed-shaft P may be rotated in
either one direction or the other; and it is
45 advantageous to make the feed-screw K with
the thread in such a direction that the drill-
ing-feed will be effected through the bevel-
gear K and larger bevel-gear m, and in this
case the bevel-gear l will be used for running
50 back the cutting-tool, and this motion will be
more rapid than the feeding motion.

The knee-plate E is made with and sup-
ported by the knees or brackets E', the ver-
tical edges of which are received between and
behind the guides 16 on the column A, which
55 guides are sufficiently strong for supporting
the knee-plate and the parts carried by the
same, and between these guides 16 the brackets
and knee-plates can be raised or lowered
by the screw Q and tubular nut Q'. This
60 screw Q is stationary and its lower end is re-
ceived into a boss projecting from the base of
the column A, and the tubular nut Q' is cap-
able of being rotated, and its upper end is
received into a web or cross-bar between the
65 two brackets E'. By rotating this nut Q in
one direction the knee-plate E can be lowered
until its under side rests upon the top of the

screw Q, and by rotating the tubular nut Q'
in the other direction the knee-plate can be
raised until the tubular nut comes nearly to
70 the top of the stationary screw Q. By this
means great latitude of motion is provided in
a small compass.

In order to rotate the tubular nut Q', a pin-
ion q and shaft passing through a sleeve or
75 socket between the knees or brackets may be
made use of, such shaft having a square upon
its outer end for the reception of a handle or
key; but when the knee-plate and the parts
carried by it are to be moved vertically and
80 progressively in milling or cutting the tubu-
lar nut Q' is rotated by power from the ex-
tension-shaft O and its universal joints, the
universal joint O² being connected to a shaft
17, Fig. 5, that passes through bearings that
85 project from one of the brackets E', and this
shaft is provided with bevel-pinions 18, gear-
ing with a bevel-wheel 19 upon a shaft 20,
that has at its inner end a bevel-gear 70, en-
gaging the bevel-wheel 71 upon the tubular
90 nut Q', and the bevel-wheels 18 are loose upon
the shaft 17, and there is a feather and clutch
between them, which clutch is moved by a
hand-lever 21 to bring either wheel 18 into
action and either raise or lower the knee-plate
95 and brackets or else arrest its movement. By
this means I am enabled to move the knee-
plate and parts carried by it automatically
or by hand or to stop the feed instantly.

Upon the knee-plate E, Fig. 6, a saddle R
100 is fitted to slide toward and from the column
A, and this saddle is similar to the slide-rest
of a turning-lathe, the edges of the knee-plate
being inclined upwardly and the saddle hav-
ing beveled ledges or clips beneath the edges
105 of the knee-plate, and there is upon the sad-
dle R a nut, through which passes the adjust-
ing-screw R', having at its outer end a han-
dle R², and this adjusting-screw R' is not cen-
tral, as usual; but it is at one side of the cen-
ter, so as not to be in the way of the screw Q,
110 and also to be at one side and out of the way
of the slotted lower end C' of the arm or pend-
ent drop C.

The swivel plate S rests upon the saddle R,
115 and there is a center pin connecting the
swivel and the saddle, and in the top surface
of the saddle there is an annular groove un-
dercut or T shaped for the reception of the
heads of the clamping-screws r. This allows
120 the swivel-plate to be turned around into any
desired position in relation to the saddle and
clamped by the screw r. Upon this swivel-
plate is a platen T, the lower edges of which
are made as dovetail ribs sliding in a corre-
125 spondingly dovetailed recess across the
swivel-plate, and there is a longitudinal ad-
justing-screw t for the platen passing through
a nut upon the swivel-plate, and such adjust-
ing-screw t has a handle at the end t', by
130 which it may be rotated, and this platen T is
adapted to receive the article to be bored,
milled, or otherwise acted upon by the tools,
and preferably the upper surface of the platen

is grooved longitudinally with undercut or **T** grooves for the reception of the heads of clamping-bolts, and there is also preferably near the center thereof an annular groove for the reception of bolts to secure a clamping-bed or other supporting device for the article to be operated upon.

If there is any looseness of the platen, the parts are liable to tremble and the operations of the tool are made imperfect. To prevent this, I employ a double-inclined gib 23, (see Figs. 1 and 13,) one face of which rests upon the inclined surface of the slide of the platen, and the other surface of which gib rests 15 against the under side of the overhanging or dovetail portion of the swivel-plate, so that by moving the gib laterally it acts as a wedge to tighten up the parts, and this lateral motion is given by screws 24 passing in through 20 the side of the swivel-plate and into notches in the outer edge of the inclined gib, and these screws prevent the gib moving endwise, and by means of these screws the gib can be set up to compensate wear and, if necessary, 25 to form a clamp that holds the platen firmly within the swivel-plate; but usually it is only necessary to set up these screws 24 sufficiently to compensate wear and prevent any looseness. This gib is much less liable to become 30 bent or injured than those gibs which are wedge-shaped longitudinally, and with such longitudinally-tapering gib it is difficult to keep a uniform bearing of the gib upon the respective parts by the end adjustment given 35 to such gib, whereas in my improvement the bearing of the gib upon the respective parts is always insured, because the gib may move laterally at any place under the action of either of the screws 24 as such gib is forced 40 into the space to take up any wear or looseness. Gibs of this character may be used on the guides 16 and other parts of the machine.

I find it advantageous to be able to act on the adjusting-screw R' by power to move the 45 saddle R in either one direction or the other. With this object in view I make a nut R^3 in the form of a screw-pinion between two downwardly-projecting lugs upon the under side of the saddle, and I rotate this nut R^3 , Fig. 50 12, by the worm-pinion 25 and bevel-gears 26 and 27, to the latter of which power is applied from the universal joint O^2 of the extension-shaft O . Hence when the worm 25 and gears 26 and 27 are being rotated and the 55 screw R' remains stationary the saddle R will be moved in one direction or the other, and it will be apparent that the direction of rotation might be changed by crossing the belts or leading them straight to drive the 60 shaft O ; but usually it is preferable to employ another bevel-gear 28, with an intermediate clutch between the gears 27 and 28, acted upon by a handle 29, so that the direction of rotation of the worm R^3 may be changed 65 by the clutch connecting either 27 or 28 with the shaft that is rotated by the universal joint O^2 , and I remark that it is preferable to fit

the universal joint of the extension-shaft O with keys, set-screws, or squares to be connected to either of the shafts that may be rotated by such extension-shaft O . Hence this extension-shaft O and its universal joints may be made to rotate the worm R^3 and move the saddle in either one direction or the other, or it may be made to rotate the tubular nut Q' 70 and raise or lower the knee-plate and parts carried by it, and such extension-shaft may be made also to give motion to the screw T' of the platen T . The screw t , Figs. 1 and 7, has on the end a handle t' , by which it may 75 be rotated. It also has a changeable gear 41 for giving motion to the revolving angle-plate, hereinafter described.

In order to actuate the feed-screw t by power, I provide a shaft with a coupling 42 at one 85 end for the universal joint O^2 and at the other end a bevel-pinion 43, gearing to the wheel 44, that is loose on the screw t , and there is a sliding clutch 45 or a key on the screw t , that can be acted upon by the hand-lever T^2 , that 90 passes through a mortise in the side of the platen and is pivoted to the under side of the top plate of the platen, and I remark that there are not openings in such top plate. Hence 95 chips and dirt cannot fall into the gearing. The feed stop-bar 47 is parallel with the screw t and crosses close above the shaft of the pion 100 ion 43, and there is a movable stop 46 on this bar 47 to come into contact with the side of the swivel-plate S and stop the feed automatically, and there is a forked arm 48 projecting from this stop-bar 47, that engages the clutch 45, and it is preferable to have the lever T^2 105 act upon this arm 48, so as to start the feed-screw t by coupling the parts by hand, and the position in which the stop 46 may be 110 clamped on the bar 47 will determine the place at which the feed will be stopped automatically.

The platen T has a central opening, so that, 110 if desired, a swivel-pin may be introduced from above to fill the hole and aid in retaining the attachment firmly in position, and this swivel-pin s is generally fixed to the attachment, such as a vise or work-bed, and the pin s is central with the groove in the 115 surface of the platen, and I provide a revolving angle-plate or vise and a bed for the same, the revolving angle-plate U being circular and its center being approximately in line 120 with the swivel-pin s , and the angle-plate and its bed can be shifted upon the platen T into any desired straight or angular position to the cutting or boring tool driven by the spindle D , and this angle-plate can be either horizontal or tipped, to a greater or less inclination, according to the work that is carried by the same, and in cases where the swivel-pin s only passes from the bed U' into the platen 125 T this platen T can be moved endwise upon the swivel-plate or laterally upon the knee-plate to bring the article that is held by the 130 plate U into any desired relation to the cutting or boring tool.

The revolving angle-plate U is circular and provided with a central tubular axis u, passing down into the cross-piece of the segmental carriers V. These carriers V are half-circles 5 described from a center which corresponds to the surface of the revolving angle-plate U, and the segmental portions of the carriers are parallel to each other and are united by a cross-piece v⁶, through which the axis u passes, 10 and the central portions of the segmental carriers are recessed for the revolving angle-plate to set into such recess, so that the surface of the angle-plate corresponds to the diametric line forming the upper edges of the 15 segmental carriers, and these segmental carriers are received into the quadrant brackets U² upon the bed U', and there are segmental undercut grooves in the segmental carriers and T-bolts v passing through the quadrant 20 brackets U² with their heads in such segmental slots, so that by loosening these bolts v the segmental carriers and the angle-plate can be swung to bring the surface of the angle-plate horizontal, vertical, or at a greater or less 25 inclination, and when this is done the parts are held firmly by screwing up the bolts v. It is now to be understood that this circular angle-plate U can be revolved upon its axis u, there being a worm-gear u' upon such axis 30 across beneath the revolving angle-plate, and passing through the segmental carriers there is a shaft W, having upon it a worm-pinion u⁴, gearing into the worm-wheel u', so that by 35 rotating this shaft W the circular angle-plate U can be revolved, and in so doing the article that is supported by such angle-plate can be rotated, and I remark that in the top surface of the circular angle-plate there are undercut grooves for the reception of bolts by 40 which the article to be acted upon is clamped to this circular angle-plate, and I provide the means next described for revolving this shaft W automatically or by hand, so that the circular angle-plate may be continuously rotated 45 to bring the article into contact with any milling-tool, or it can be rotated progressively to present the article held by it to milling or boring tools to act upon such article in boring separate holes or milling progressively 50 any portions of the surfaces. This tool is adapted to cutting gear-teeth at any desired bevel or inclination or to boring equidistant holes or like operations.

Fastened upon the end of the shaft W is a 55 crank-arm 30, by which said shaft W can be rotated, and at the outer end of this arm is a sliding pin 31, the end of which also forms a handle by which the crank can be rotated, and the pin is adapted to pass into the perforated 60 divided disk W', such as is made use of in gear-cutting machines and similar tools, and the pitch of the worm-pinion u⁴ in relation to the worm-gear u' is such that the perforated divided disk can be used conveniently in turning the circular angle-plate and the gear or 65 other article supported by the same progress- ively to cut any desired number of teeth on a gear or to bore any desired number of holes or to do any similar work. In order to rotate this shaft W progressively during the cutting 70 or milling operation performed by the tool in the spindle D, I have carried the end of the shaft W which is opposite that provided with the crank-arm 30 through the segmental carriers and shaped it to receive the coupling 75 end of the universal joint O², and also on the other end I provide a gear-wheel 33, permanently fastened to the shaft W, and the gears 34 and 35 extend to the shaft 36, that may be revolved by any suitable power. This shaft 80 36 is supported by the bed U', and it is advantageous to employ a journal 37 for the gear-wheel 34, said journal 37 being supported by the links 39, which links at their outer ends surround the shafts W and 36 in order 85 that the teeth of the train of gearing may always remain properly engaged, whether the circular angle-plate U is horizontal or tipped into a more or less angular position.

I have represented the shaft 36 as rotated 90 by bevel-gears 50 51, and the bevel-gear 51 is connected with a straight gear 52, which receives motion from the gear 53 on the movable arm 54, and this receives its motion from the changeable gear 41 upon the feed-screw t 95 of the platen T, such gear 41 receiving its motion from the extension-shaft O, as described. Hence it will be apparent that the circular angle-plate U can be revolved at any desired speed, according to the position of the belts 100 upon the cones or pulleys or according to the size of the gear 41, such gear 41 being changeable to give the desired speed of revolution. By this arrangement of gearing the platen can be moved endwise at the same time that 105 the angle-plate is revolved, and the article held on such angle-plate can be milled or otherwise acted upon in a spiral line, either conically or cylindrically.

If the character of the article that is being 110 acted upon is such that the extension-shaft O and universal joint O² can reach the shaft W, such joint O² can be connected directly to the projecting end thereof—that is, at the opposite side of the attachment from the crank- 115 arm 30.

I claim as my invention—

1. The combination, with the column and standards, of the spindle D, the tool-holding tube within the spindle, a gear-wheel or pulley around the spindle, a key connecting the gear-wheel spindle and tool-holding tube, the latter being slotted longitudinally for the inner end of the key, a cone of pulleys loose upon the spindle, and means for connecting 120 the cone of pulleys with the gear-wheel, substantially as set forth.
2. The cone of pulleys having a separate tubular hub with pinion-teeth at one end thereof, the pulleys being permanently connected to the tubular hub, in combination 125 with the spindle and the gear-wheel connected 130 with the spindle.

with the spindle, and a movable connection between the gear-wheel and the cone of pulleys, substantially as set forth.

3. The spindle and its supporting column and standards, in combination with the cone of pulleys loose upon the spindle and a pinion upon the hub of the pulleys, a gear-wheel connected with the spindle, a movable connection between the gear-wheel and the cone of pulleys, a counter-shaft, and two movable gears thereon adapted to be brought into gear with the pinion or with the gear-wheel upon the spindle, respectively, or both brought into gear, substantially as set forth.

15 4. The combination, with the tool-holding spindle and means for revolving the same, of a column or standard having a split tubular socket at the upper end and clamping-screws, a supporting-arm passing through the tubular socket and adapted to be clamped therein, a pendent drop, and a split tubular socket at the end of the supporting-arm for the reception of the upper end of the pendent drop and clamp-screws, substantially as set forth.

25 5. The combination, with the column, the tool-holding spindle, and means for revolving the same, of a knee-plate, knees or brackets for supporting the same, guide-slides upon the column for the brackets and knee-plate and in which they can be moved vertically, a stationary screw, and a tubular nut capable of being revolved for raising and lowering the brackets, knee-plate, and parts supported by the same, substantially as set forth.

35 6. The combination, with the vertical column, the knee-plate, bracket, and guides for supporting the same upon the column, of a screw and nut for raising and lowering the knee-plate and brackets, the saddle resting upon and sustained by the knee-plate, and a screw and nut for moving the saddle, such screw and nut being in a different plane from the vertical screw to allow the adjusting-screw for the saddle to be at one side of the screw that raises and lowers the knee-plate when the knee-plate is lowered, substantially as set forth.

45 7. The combination, with the vertical column, the knee-plate, brackets, and guides, of a saddle, a screw for moving the saddle upon the knee-plate, a worm-pinion forming a nut for the screw, and a worm-shaft and gearing for rotating the same and for revolving the pinion and nut in moving the saddle upon the knee-plate, substantially as set forth.

55 8. The combination, with the tool-holding tube and spindle, the column, and guides, of the brackets, knee-plate, saddle, a swivel-plate resting upon the saddle, a screw for adjusting the saddle, bolts for securing the swivel-plate to the saddle, a platen resting upon and provided with dovetail connections to the swivel-plate, and an adjusting-screw for moving the platen upon the swivel-plate, substantially as set forth.

9. The combination, with the platen having

dovetail supports, of a gib thicker at one edge than the other to form a wedge and notched upon its thicker edge, and adjusting-screws acting upon the gib at the notches for moving such gib laterally and preventing looseness in the sliding parts, substantially as set forth.

10. The combination, with a support and a platen or article sliding within the support, of a gib thicker at one edge than at the other and of a length corresponding to the supporting parts, and screws acting at right angles to the length of the gib to move the same laterally in adjusting the gib to compensate wear, substantially as set forth.

15 11. The combination, with a vertical column, a knee-plate, brackets, and supporting-guides, of a supporting-arm, a split tube upon the standards of the column, through which the supporting-arm passes, clamps for holding such supporting-arm, a pendent drop at the end of the supporting-arm adapted to receive the boring-bar or other rotating tool, the lower end of the pendent drop being slotted vertically, and a screw upon the knee-plate passing through the slot of the pendent drop for steadyng or securing the same, substantially as set forth.

20 12. The combination, with the column or standards and the spindle and means for rotating the same, of a tool-holding tube within the spindle, a tubular nut connected with the tool-holding tube, a screw for acting upon the tubular nut to move the same endwise, and a gear-wheel driven by friction for acting upon the tubular screw, whereby the endwise feeding operation upon the tool is arrested when the resistance is sufficient to prevent the screw being rotated by the friction applied to its gear, substantially as set forth.

25 13. The combination, with the column or standards and the spindle and means for rotating the same, of a feed-shaft in the same horizontal plane, or nearly so, as the spindle, but at an inclination thereto, a hand-wheel upon one end of the feed-shaft, a gear-wheel upon the other end of the feed-shaft, friction-washers for connecting the gear-wheel to the shaft, a tool-holding tube within the spindle, a tubular nut connected with the tool-holding tube, a tubular screw for acting upon the nut, and a gear-wheel upon the tubular screw gearing to the frictional gear upon the feed-shaft, substantially as set forth.

30 14. The combination, with the column or standards and the spindle and means for rotating the same, of a feed-shaft, a screw acting upon the tool-holder of the spindle, gearing for connecting the feed-shaft and screw, a worm-pinion upon the spindle, a worm-gear and bevel-gear receiving motion from the worm, bevel gear-wheels loose upon the feed-shaft, and a coupling for connecting either of the bevel-gears to the feed-shaft, substantially as set forth.

35 15. The combination, with the column or standards and the spindle supported by the same, of a pulley loose upon the spindle, a

counter-shaft, gearing for connecting the counter-shaft and pulley, a gear-wheel connected with the spindle, a movable pinion upon the counter-shaft for connecting or disconnecting such counter-shaft and gear-wheel on the spindle, pulleys and belts driven by the counter-shaft, a feed-shaft, universal joints and extension-shaft, a platen and saddle for supporting the article to be operated upon, a screw for giving motion to the platen, and gearing for connecting the extension-shaft and universal joints with the screw, substantially as set forth.

16. The combination, with a spindle, a column and standards for supporting the same, and means for rotating the spindle and the tool therewith connected, of a knee-plate and means for supporting the same upon the column, a screw and nut for raising the knee-plate and the parts supported by the same, a feed-shaft, a counter-shaft, gearing for driving the counter-shaft from the spindle, pulley-belts and pulleys for connecting the counter-shaft and feed-shaft, an extension-shaft and universal joints connected with the feed-shaft, gearing for rotating the screw-nut and raising and lowering the knee-plate, and a connection between such gearing and the universal joint of the extension-shaft, substantially as set forth.

17. The combination, with the platen, of a circular angle-plate, segmental carriers and connection between them for the axis of the circular angle-plate, a bed with quadrant brackets passing inside the segmental carriers, and clamping-screws whereby the circular angle-plate can be set horizontally or at any desired angle for supporting the article to be operated upon, substantially as set forth.

18. The combination, with the circular angle-plate having an axis, of the segmental carriers recessed for the reception of the circular plate and having a connection between them through which the axis of the angle-plate passes, a worm-gear upon the said axis, a shaft and worm for rotating the angle-plate, said shaft passing through the segmental carriers, and a handle or a gear for rotating such shaft, substantially as set forth.

19. The combination, with the circular angle-plate and its axis, of segmental carriers having a cross-piece between them for the axis of the angle-plate, a gear upon said axis, a cross-shaft and worm for actuating such gear and revolving the angle-plate, a bed and quadrant brackets for supporting the segmental carriers, a gear upon the shaft, a driving-gear, an intermediate gear, and connecting-links for retaining the gears in mesh with each other and allowing the angle-plate to be moved into a horizontal or inclined position, substantially as set forth.

20. The combination, with the platen T and its feed-screw, of the stop-bar parallel with

the feed-screw, an arm on the stop-bar, bevel-gearing to drive the feed-screw, a coupling acted upon by the arm of the stop-bar, and a lever below the top plate of the platen to act upon the stop-bar and coupling, such lever projecting through a mortise in the side of such platen, substantially as set forth.

21. The combination, with the column and standard, of a spindle D, the tool-holding tube within the spindle, a driving-wheel around the spindle, and a key connecting the wheel-spindle and tool-holding tube, the latter being slotted longitudinally for the inner end of the key, substantially as set forth.

22. The cone of pulleys having a tubular hub that is a separate piece from the conical shell and provided with pinion-teeth cut at one end of the tubular hub, the two parts of the cone of pulleys being secured together, substantially as specified.

23. The combination, with the feed-shaft, of a column, a knee-plate supported by the column, a screw and gearing for raising and lowering the knee-plate, a saddle with screw and gearing for moving the same, a platen and screw and gearing for moving the same, and an extension-shaft and universal joints connected with the feed-shaft and adapted to give motion to either the parts that move the platen, the saddle, or the knee-plate, substantially as set forth.

24. The combination, with the feed-shaft and the supporting-column, of a knee-plate and screw and gearing for raising and lowering the same, a saddle and a platen, the respective screws and gearing for moving the same, and an angle-plate and gearing for revolving the same, and an extension-shaft and universal joints connecting with the feed-shaft and adapted to give motion to either the platen, the knee-plate, the saddle, or the angle-plate, substantially as set forth.

25. The combination, in a universal milling-machine, of a column, a feed-shaft, rests for supporting, holding, and presenting the work to the drilling or milling tools, and an extension-shaft and universal joints connected with the feed-shaft and adapted to be connected with either of the moving devices for presenting the work to the boring or milling tools, substantially as set forth.

26. The combination, with the saddle or slide-rest and a screw and handle for moving the saddle, of a worm-pinion connected with the saddle and forming a nut for the screw, and a worm-shaft and means for rotating the same and revolving the nut to move the saddle, substantially as set forth.

Signed by me this 17th day of February, 1891.

ALBERT D. PENTZ.
